UNITED STATES PATENT OFFICE.

ALFRED BOUGAULT, OF PARIS, FRANCE, ASSIGNOR TO SOCIÉTÉ FRANÇAISE DE CONSTRUCTIONS MECANIQUES, (ANCIENS ETABLISSEMENTS CAIL,) OF PARIS, FRANCE.

PROCESS OF MANUFACTURING GAS.

SPECIFICATION forming part of Letters Patent No. 770,554, dated September 20, 1904.

Application filed June 17, 1903. Serial No. 161,933. (No specimens.)

To all whom it may concern:

Be it known that I, ALFRED BOUGAULT, engineer, a citizen of the French Republic, residing at Paris, Department of the Seine, France, (whose post-office address is 21 Rue de Londres, in the said city,) have invented certain new and useful Improvements in the Manufacture of Poor Gas, of which the following is a specification.

10 This invention has for its object to provide a producer for use in the manufacture of poor gas for heating or motive power purposes, which apparatus is capable of utilizing fuel of all kinds, and especially coal, which 15 yields a fusible residue.

In accordance with this invention the gas-producer is provided with means such that the temperature in any part of the producer is prevented from exceeding 1,200° or 1,300° 20 centigrade, so that the fusion of the residue (resulting in the production of clinker) is avoided. This result is obtained by supplying the lower part of the combustion-chamber with gas mixed with the air in such 25 portion that (its temperature being taken into account) the gaseous products and solid residues of the combustion do not attain such temperature as would cause the production of clinker. The gas which is used is that produced in the gas-producer, the proportion of such gas being greatly in excess of that which would form with the air with which it is mixed, an entirely combustible mixture. This gas may be derived from the same or 35 from another gas-producer and previous to use may be stored or not in a gas-holder.

When the gas is taken from the same gas-producer, a by-pass channel or by-pass channels takes or take the gas from the producer 40 at a point above the solid fuel therein and opens or open into the lower part of the producer. The air being mixed with the gas in the said channel or channels, the motion of the gas and air is maintained in the channel 45 or channels and the velocity thereof adjustable by any suitable means. For example, a fan may be used or the air previously compressed may by means of an injector be

forced with the gas into the furnace. The admission of air to the gas thus derived from 50 the producer may cause the combustion of a portion of this gas before the mixture reaches the solid fuel. This portion cannot exceed that which depends on the proportion of the air, for the gas is always in excess; but it remains under this limit or comes nearer to it 55 according as the arrangement of the apparatus, the regulation of the temperature in the various parts of the producer, the amount of water, or the rate of working oppose or facilitate combustion. If this premature combination reaches the limit, the gasification of the solid fuel is effected solely by a reduction

process—that is to say, instead of the oxidizing and reducing zones which ordinarily succeed each other in the combustion of coal there is a reducing zone only. The water which it is advisable to allow to take part in the reactions occurring within the producer in a proportion depending on the nature of 60 the fuel and the kind of gas to be obtained is introduced into the by-pass channel or channels either as steam or in the liquid state, the temperature of the by-pass channel or channels being sufficient to evaporate the water. 65 When a fan is employed to promote the circulation of the gases, water in the liquid state may be introduced at the fan itself, so as to reduce the heating of the working parts of the fan which come in contact with the gases. 70 75

The whole of the gas-producer may be maintained at a pressure that is greater or less than that of the atmosphere (according as it is desired to regulate the output of the produced gas) by means either of a second fan 80 forcing air into the producer or of a suction apparatus (fan, pump, or the like) drawing the produced gas from the producer and forcing it into the gas-holder or into the mains for utilization, or if the gas-producer be used for 85 supplying gas to a gas-motor the effect can be gained by the suction-strokes of the gas-motor. Whatever arrangement be adopted in this respect the mixture, consisting of the gas taken from the upper part of the producer, 90 the air introduced thereinto, the products of 95

the partial combustion which this introduction of air may have caused, and the water, more or less completely evaporated, must penetrate the solid fuel at the base thereof through-
 5 out a large surface, so that notwithstanding the pulverulent character of the ash or residue the resistance to penetration is not too great. For this purpose the lower part of the producer is provided with an internal
 10 arched recess or several such recesses into which the solid fuel and ash or residue spread and form an incline or inclines. The parts of the recess or recesses bounded at the upper part by the arch or arches and at the
 15 sides by the wall or walls of the producer and the inclined wall or walls of the solid fuel and ash or residue constitute an inclosure or inclosures which is or are protected from external cooling influences and into which the
 20 by-pass channel or channels opens or open.

The improved gas-producer according to this invention differs from producers in which the combustion is promoted by blowing air into the lower part of the fuel and taking the
 25 gas (containing the products of distillation of the fuel) from the upper part of the gas-producer and returning it to the fuel at a higher level. The latter arrangement has for its object to effect the dissociation of the tar, and
 30 if it at the same time cools the mass of fuel it does it only above the level at which the gas is returned, the high-temperature zone in which the clinker is formed existing still below the said level. The system according to this
 35 invention is entirely different, as it does not permit the combustion to take place at a high temperature in any part of the producer, because the air is diluted by a large excess of gas. The gas-producer according to this in-
 40 vention also differs from producers in which in order to avoid external losses of combustible gases while the producer is being charged or the fire is raked the escaping gases are turned onto the blast-mains through a steam-
 45 blower. Considering the quantity of steam which the gas-producer can receive, the quantity of gas that can be thus admixed with the air-blast is quite insufficient to produce a perceptible lowering in the tempera-
 50 ture.

When several gas-producers are connected so as to form a set, they may be so arranged that one part of them supplies only the gas intended to be diluted with air for the whole
 55 set, while the other producers are alone connected to the receiving-mains for the produced gas. The producers may also when they are connected each separately to the external mains be provided with a single by-pass chan-
 60 nel common to all of them and taking the gas from the upper part of each producer and opening into the lower part of the several pro-
 65 ducers, the introduction of the air and the addition of water being effected in an apparatus common to all the producers.

The accompanying vertical sections show a few arrangements (merely by way of example) of the improved gas-producer in accordance with this invention.

Figure 1 shows a gas-producer the shaft of 70 which is made narrower at its lower part *a* than above, this narrower part being followed by a gradual enlargement *b*. The mixture of air and gas is kept in motion by the action of a fan *c*, drawing gases from the upper part 75 of the producer and forcing them into a passage or passages, such as at *d*, which opens or open into a space immediately below the narrow part *a* of the producer-shaft.

Figs. 2 and 3 show another arrangement of 80 the lower part of the gas-producer. The two arched spaces *e e'*, which cause the fuel and ash or residue to spread and form inclines, are diametrically opposite each other and above the openings for the introduction of the 85 mixture of air and gas.

In the arrangement shown in Fig. 4 the gas-producer receives from an external apparatus the gaseous mixture required to maintain the combustion and is provided with only one 90 lower arched space *g*, leaving on each side thereof a passage for the descent of the fuel and ash or residue, the circulation of the mixture of air and gas being effected by a compressed-air injector or injectors *f*. 95

Having now particularly described and ascertained the nature of this invention and in what manner the same is to be performed, I declare that what I claim is—

1. The hereinbefore-described process of 100 manufacturing poor gas, which consists in mixing gas-producer gas with atmospheric air, the proportion of such gas being in excess to that of the air, and then in forcing the mixture into the solid fuel in a gas-producer at 105 substantially the base of such solid fuel.

2. The hereinbefore-described process of manufacturing poor gas, which consists in removing the gas above the fuel from a gas-producer, mixing such gas with atmospheric air, 110 the proportion of gas being in excess to that of the air, and then in forcing the mixture into the solid fuel in said gas-producer at substantially the base thereof.

3. The hereinbefore-described process, 115 which consists in mixing gas-producer gas with atmospheric air, the proportion of gas being in excess to that of the air, and then in forcing the mixture, in the presence of a suitable hydrating agent, into the solid fuel in a 120 gas-producer, at substantially the base of said solid fuel.

In testimony whereof I have hereunto set my hand in presence of two subscribing witnesses.

ALFRED BOUGAULT. [L. S.]
